ROBERT K. WINNING, OF WAUWATOSA, WISCONSIN, ASSIGNOR TO CLUM MANUFACTURING COMPANY, OF MILWAUKEE, WISCONSIN, A CORPORATION OF WISCONSIN

HANDLE CONNECTION

Application filed January 24, 1927. Serial No. 163,084.

This invention relates to improvements in handle connections. The invention is particularly applicable to the connection of choke rod handles to Bowden wire control mechanism for the adjustment of carburetor valves or the like. A device in which the structure herein disclosed is useful is shown in my co-pending application, Serial No. 79,760, filed January 7, 1926, United States Letters Patent No. 1,739,812 dated December 17, 1929.

It has proven a comparatively difficult and expensive matter to provide adequate connection between a Bowden wire and a handle rod within the limited confines of the tubular housing within which such a rod is adjustable.

It is the object of the present invention to provide a simple, novel and inexpensive form of connection suitable for this purpose and adapted to maintain the Bowden wire in axial alignment with the handle to which it is connected, practically all backlash being eliminated.

25 In the drawings:

Figure 1 is a side elevation of a handle and Bowden wire operatively connected in accordance with this invention.

Figure 2 is an enlarged detail view in side elevation of the end of the Bowden wire.

Figure 3 is an enlarged detail view in plan of the end of the handle.

Figure 4 shows an enlarged fragmental section through the end of the handle to expose its construction.

Figure 5 is a view similar to Figure 4 illustrating the manner of application of the Bowden wire to the handle.

Like parts are identified by the same reference characters throughout the several views.

The handle device in its entirety is designated by reference character 10 and includes a knob 11 and a rod 12. The wire at 13 is pushed or pulled by the handle through a flexible housing (not shown) to operate a control of some sort (not shown). The usual use for a device of this character is to operate the choke control of the carburetor of an automobile. The invention relates particu-

larly to the connection between the Bowden wire 13 and the rod portion 12 of the handle.

In order to make a connection in accordance with this invention, the handle rod 12 is first channeled from above and below at 14 and 15. These channels open to the end of the rod and the intervening web 16 is bored to provide an opening 17 affording communication between the handles.

The Bowden wire has two portions 19 and 20 which are offset laterally to approximately equal distances at opposite sides of the axis of the wire. The distance between the offset portions 19 and 20 as measured along the transverse connecting member 21 is approximately equal to the thickness of the web 16.

To effect a connection between the parts above described the Bowden wire 13 has its end 20 introduced through opening 17 in the handle with the Bowden wire in approximately the relative position with respect to the handle in which it is illustrated in dotted lines in Figure 1. The portion 20 having penetrated to the limit of movement possible thereto in this position of the parts, the wire and handle are now manipulated into alignment to cause the transverse portion 21 of the wire to enter the opening 17. With the parts in alignment, it will be found that the portion 20 of the wire will lie along the upper surface of web 16 and will be closely confined between the walls of channel 14 while the portion 19 of the wire will abut the under surface of web 16 and will be closely confined between the walls of channel 15. As shown in Fig. 5 the diameter of the aperture 17 corresponds closely with the diameter of the wire. The length of the offset 22 is such that the unbent portions of wire 13 will be substantially aligned with the axis of rod 12 and with the center line of web 16. The wire 13 and member 15 are maintained in their assembled relation by the tubular housing 25 which confines portions 19 and 20 of the wire closely within the respective recesses 14 and 15.

Since the channels 14 and 15 and the peculiar conformation of the end of wire 13 can readily be prepared prior to the assembling operation, and since no machine operations are necessary in the course of assembly, it

will be obvious that much time, labor, and expense is saved by the present invention. It has been found, moreover, that the wire and handle do not tend to become misaligned or distorted in use and, consequently, all thrusts on the handle are transmitted along the axial line of the wire.

I claim:

1. In a device of the character described, 10 the combination with a rod having longitudinally extending channels opening to its end on opposite sides thereof, and an intervening web apertured to afford communication between said channels, of a wire closely fitting said channels and having a portion disposed in one of said channels in substantial contact with one side of said web, a transverse portion extending through the aperture of said web, and a third portion parallel to said 15 first mentioned portion and disposed in the other of said channels adjacent the other face of said web, said first and third portions extending in opposite directions along said web from said transverse portion, said wire being substantially wholly within the projected diameter of said rod and being rigidly connected therewith through its engagement in said aperture and its contact with the rod at each side thereof.
2. A rod and wire connection comprising 20 the combination with a rod having diametrically opposite longitudinally extending slots and an intervening web provided with an aperture affording communication between the said slots and substantially corresponding in diameter to the width of the respective slots, of a wire having offset portions disposed in the respective slots and an intervening portion extending through said aperture, 25 the mutually offset portions of the wire being closely confined in the respective slots and supported therein with their exposed surfaces conforming substantially to the projected periphery of said rod.
